(57) **CLAIM**

The ornamental design for a system for monitoring an area behind a vehicle, as shown and described.

DESCRIPTION

FIG. 1 is a front perspective view of a system for monitoring an area behind a vehicle showing my design.

FIG. 2 is a bottom perspective view of the system for monitoring an area behind a vehicle of FIG. 1.

FIG. 3 is a front view of the system for monitoring an area behind a vehicle of FIG. 1.

FIG. 4 is a rear view of the system for monitoring an area behind a vehicle of FIG. 1.

FIG. 5 is a right side view of the system for monitoring an area behind a vehicle of FIG. 1.

FIG. 6 is a left side view of the system for monitoring an area behind a vehicle of FIG. 1.

FIG. 7 is a top view of the system for monitoring an area behind a vehicle of FIG. 1; and,

FIG. 8 is a bottom view of the system for monitoring an area behind a vehicle of FIG. 1.

The broken line showing of a cord is for illustrative purposes only and forms no part of the claimed design.
